[57] CLAIM

The ornamental design for a loose-fill packing element,
as shown.

DESCRIPTION

FIG. 1 is a perspective view of a loose-fill packing element showing my new design;

FIG. 2 is a top plan view thereof;

FIG. 3 is an end elevational view thereof;

FIG. 4 is a cross-sectional view taken along line 4—4 of
FIG. 1; and

FIG. 5 is a bottom plan view thereof.

FIG. 1

FIG. 2

FIG. 5

FIG. 3

FIG. 4
